UNITED STATES PATENT OFFICE.

WEBB JAY, OF CHICAGO, ILLINOIS.

PRIMING ATTACHMENT FOR EXPLOSIVE-ENGINES.

1,081,534,

Specification of Letters Patent.

Patented Dec. 16, 1913.

Application filed January 31, 1912. Serial No. 674,549.

To all whom it may concern:

Be it known that I, WEBB JAY, a citizen of the United States, residing at Chicago, in the county of Cook and State of Illinois, have invented certain new and useful Improvements in Priming Attachments for Explosive-Engines, of which the following is a specification.

My invention relates in general to explosive engines, and more particularly to attachments for facilitating the starting of such engines.

Considerable difficulty is often experienced in starting explosive engines, such, for instance, as those commonly used to propel automobiles, especially in cold weather when the liquid hydrocarbon does not vaporize as readily as in warm weather. The relative proportions of fluid hydrocarbon and air, which form the most efficient explosive mixture for running an engine after it has started, are often not sufficiently highly explosive to initiate the explosions when the engine is cranked. It is, therefore, frequently necessary to inject directly into an engine cylinder a small quantity of liquid hydrocarbon in order that the explosions may be started. Various devices have been proposed for supplying to the engine cylinder a priming charge of liquid hydrocarbon, such, for instance, as a hand pump, a cup located above the manifold to which hydrocarbon is supplied by hand, and means for utilizing the compression in the cylinders to inject the priming charge of hydrocarbon into the manifold.

In my copending application, Serial No. 602,622, filed January 14, 1911, I have disclosed a priming device for explosive engines in which the priming charge is lifted into the engine cylinder solely by the partial vacuum created in the engine cylinder by the reciprocation of the piston therein; and my present invention relates to an improvement in the invention covered by my said copending application and resides in providing a chamber in the priming conduit adjacent the manifold into which hydrocarbon is drawn by the suction created in the engine cylinder, or cylinders, coincidentally with the drawing of the priming hydrocarbon into the engine cylinder, thereby auto-

matically storing a small quantity of hydrocarbon at a point adjacent the manifold so that it will flow by gravity or be quickly drawn into the engine cylinder by a very slight rotation of the starting crank, without requiring a sufficient suction being created to lift the hydrocarbon from the point where the priming conduit connects with the hydrocarbon supply to the manifold each time the engine is started.

My invention also consists in other features of construction which will be herein-after more fully disclosed in the specification and specifically pointed out in the claims.

In the accompanying drawings I have illustrated my invention as embodied in a convenient and practical form, in which—

Figure 1 is a side elevational view of a four-cylinder engine provided with my improved priming attachment. Fig. 2 is an enlarged vertical section through the priming chamber and adjacent parts; and Fig. 3 is a detail horizontal section taken on the line 3—3 of Fig. 2.

The same reference characters are used to designate the same parts in the several figures of the drawing.

Reference letter A indicates the crank case, and reference characters A', A², A³, and A⁴ designate the cylinders of a four-cylinder engine.

B designates the crank shaft, and C a portion of the supporting frame of the engine.

D indicates the radiator, and E the dashboard at the front of an automobile, between which and the radiator it is usual to locate the engine in automobiles as generally constructed.

F designates the carbureter, to which leads the conduit G extending from a supply of gasoline or other liquid hydrocarbon,

H indicates the air intake leading to the carbureter.

K indicates the conduit leading from the carbureter, through which the explosive mixture is supplied to the engine cylinders.

L indicates a manifold, with which the conduit K communicates and from which extend branch conduits L', L², L³, and L⁴, to the respective cylinders.

The parts above described do not in themselves constitute my invention, as they are such as are commonly used in propelling automobiles.

5 While I have illustrated and described the above parts of an automobile engine as consisting in certain specific structures, yet it will be understood that my invention is not limited in its application to any specific 10 form of engine or of its constituent parts, but that it is applicable to explosive engines generally, whether employed to propel automobiles or for other purposes.

Reference letter M indicates a priming 15 conduit for supplying the motive fluid, whether it be gasoline or other forms of liquid hydrocarbons, around the carburetor to the engine cylinders when the engine is to be started. This conduit communicates at its 20 lower end with a supply of motive fluid, such, for instance as the conduit G, which leads from the fuel reservoir to the carburetor. The upper end of the conduit M leads to a chamber or reservoir N through any 25 suitable connection, such, for instance, as a screw-threaded nipple n, to the end of which is clamped the upper end of the conduit M by an exteriorly screw-threaded coupling m. The conduit M communicates with the in- 30 terior of the chamber N at a point above the bottom thereof, preferably adjacent its top. A conduit O also communicates with the interior of the chamber N through any suitable connection, such, for instance, as an 35 exteriorly screw-threaded nipple n', to which the conduit O is clamped by an interiorly screw-threaded coupling o'. The other end of the conduit O is connected to a valve casing P in any suitable manner, as by means 40 of an exteriorly screw-threaded nipple p, to the end of which is clamped the adjacent end of the conduit O by an interiorly screw-threaded coupling o. The valve casing P is provided with a valve seat P' intermediate 45 of the passage p', with which the conduit O communicates, and the passage p² leading to the manifold, as shown in Fig. 3.

Located within the chamber N is a curved tube R, one end of which is open and located 50 adjacent the bottom of the chamber, while the other end communicates with a passage N², preferably formed in the lower wall of the chamber N and communicating, through a valve seat n², with a passage n³ leading to 55 the passage p² which communicates with the manifold L. A valve s² co-operates with the valve seat n² and is preferably of the needle type. The stem S of the valve s² is in screw-threaded engagement with the passage N² 60 and extends forwardly of the automobile through the radiator D to a convenient point, where it is provided with a suitable device S' for facilitating its rotation to close or open the valve s². A suitable stuffing box

surrounds the valve stem to prevent leakage 65 from the chamber N. A valve t co-operates with the valve seat P' and is also preferably of the needle type, and is provided with a stem T in screw-threaded engagement with a nipple t' projecting from the valve casing. 70 A suitable stuffing box t² surrounds the valve stem T and engages the nipple t' to prevent leakage. The valve stem T extends to a point where it may be conveniently operated, as, for instance, through the dash- 75 board E, where it is provided with a device T' to facilitate its rotation to thereby open or close the valve t. The chamber N is pref- 80 erably provided with a removable cap N', so as to permit the location within the chamber 85 of the short curved tube R. The chamber N may be conveniently supported upon the valve casing through the engagement of a screw-threaded nipple around the passage n³ with a correspondingly interiorly screw- 85 threaded recess in the valve casing P. The valve casing may be conveniently mounted upon the manifold through any suitable connection, as shown in Fig. 3.

The operation of my improved priming 90 attachment for explosive engines is as fol- 95 lows: Assuming that the valves s and t are closed and it is desired to start the engine, the valve t is opened by rotating the valve stem T. This places the priming conduit in direct communication with the manifold L through the medium of the chamber N, conduit O—which is in effect a continuation of the priming conduit M—valve casing P, and passages p' and p² therein. The start- 100 ing crank is rotated in the usual manner, which reciprocates the pistons within the cylinders and creates sufficient vacuum therein to lift the hydrocarbon around the carburetor directly into the engine cylinders, 105 where it is readily exploded through the usual ignition system. The valve t may be allowed to remain open to a greater or less extent after the engine has been start- 110 ed, in order that the normal explosive mixture supplied to the engine through the carburetor may be supplemented by the more highly explosive fluid delivered through the priming conduit, until such time as the engine cylinders have become 115 warm enough to insure the normal vaporization of the hydrocarbon. The valve t may then be closed and the engine operated in its normal manner by the explosive mix- 120 ture supplied from the carburetor.

During the above operation, incident to the starting of the engine, liquid hydrocarbon is drawn through the priming conduit M into the reservoir or chamber N at the same time that it is drawn through the conduit O to the manifold. Upon a subsequent starting of the engine it is therefore merely necessary to open the valve s, by rotating 125

the stem S, and to then crank the engine, which draws the liquid hydrocarbon stored in the chamber N through the passage N², past the valve seat n², and through the passages n³ and p² into the manifold.

It is therefore merely necessary to rotate the starting crank very slightly, as it takes very little suction in the engine cylinders to draw the gasolene from the chamber N through the curved tube or siphon R and communicating passages into the manifold.

Before the engine is stopped the valve t should preferably be opened, in order that the engine may itself automatically lift the priming liquid hydrocarbon through the conduit M into the reservoir or chamber N and also through the manifold into the engine cylinders, so as to enable the engine to be subsequently started by merely closing

the ignition circuit. Should, however, the engine not subsequently start by merely closing the ignition circuit, it will be merely necessary to slightly rotate the starting crank in order to draw the liquid hydro-

carbon from the chamber N into the cylinders and insure the practical instantaneous starting of the engine. Should, however, the operator prior to stopping the engine fail to open the valve t, and consequently fail to

automatically supply to the engine cylinders a priming charge ready for a subsequent starting of the engine, it is merely necessary to slightly crank the engine, sufficient to draw a priming charge from the chamber N in the engine cylinders, it being unnecessary to crank the engine to the extent requisite during the priming charge from the point at which the priming conduit M communicates with the fuel supply.

From the foregoing description it will be observed that I have invented an improvement in priming devices for explosive engines by means of which a priming charge will be automatically stored at a point adjacent the engine cylinder, so that a very slight cranking is sufficient to draw the priming charge into the engine cylinder and initiate the explosion therein. In fact, the position of the reservoir in which the liquid

fuel is trapped may, under certain circumstances, supply the priming fuel to the engine cylinders by gravity, so that the mere opening of the valve from the reservoir to the engine cylinder, and the subsequent

closing of the ignition circuit, will start the explosions, without the necessity of even slightly cranking the engine.

While I have described my invention with more or less minuteness and as being embodied in certain precise forms, yet it will be understood that I do not desire to limit myself thereto unduly, or any more than is pointed out in the claim. On the contrary, I contemplate all proper changes in form,

construction, and arrangement, the omission of immaterial parts, and the substitution of equivalents, as circumstances may suggest or necessity render expedient.

I claim:

1. The combination with an explosive engine, of a closed reservoir containing liquid fuel for priming the cylinder, means connecting said reservoir with a supply of liquid fuel and with the engine cylinder, whereby the suction created in the cylinder by the reciprocation of the piston therein automatically stores liquid fuel in said reservoir preparatory to subsequently starting the engine, and means for supplying fuel from said reservoir to the engine cylinder.

2. The combination with an explosive engine of a closed reservoir containing liquid fuel for priming the engine cylinder, a conduit leading to said reservoir from a supply of liquid fuel, and from said reservoir to the engine cylinder, whereby the suction created in the cylinder by the reciprocation of the piston stores liquid fuel in said reservoir, and a conduit leading from said reservoir to the engine cylinder.

3. The combination with an explosive engine having a manifold communicating therewith of a reservoir containing liquid fuel for priming the engine cylinder, a conduit leading to said reservoir from a supply of liquid fuel and from said reservoir to the manifold of the engine cylinder, whereby the suction created in the cylinder by the reciprocation of the piston therein stores liquid fuel in said reservoir, a second conduit leading from a point adjacent the bottom of said reservoir and communicating with the engine cylinder through the manifold, and means for separately controlling said two conduits.

4. The combination with an explosive engine, comprising a cylinder, a manifold communicating therewith and a reciprocating piston therein, of a carburetor, a conduit leading from the carburetor and communicating with the manifold for normally supplying an explosive mixture to the cylinder, a conduit independent of the conduit from the carburetor leading from a supply of hydrocarbon and communicating with the manifold, a reservoir forming part of said last mentioned conduit located adjacent to the engine cylinder, a valve in said last named conduit intermediate said reservoir and engine cylinder, another conduit leading from a point adjacent the bottom of said reservoir and communicating through the manifold with the cylinder, and a valve for controlling said last conduit.

5. The combination with an explosive engine, comprising a cylinder, a manifold communicating therewith and a reciprocating piston therein, of a carburetor, a conduit

leading from the carbureter for normally supplying an explosive mixture through the manifold to the cylinder, a priming conduit by-passing the carbureter and leading from a fuel supply to the manifold, a reservoir forming part of said priming conduit for automatically trapping therein a priming supply of fuel adjacent the engine cylinder, and means for controlling the flow of said trapped fuel to the engine cylinder. 10
In testimony whereof, I have subscribed my name.

WEBB JAY.
